DOUBLE-WALLED VACUUM CONTAINER

Arthur H. Payson, Norwich, Conn., assignor to
The American Thermos Bottle Company, Nor-
wich, Conn., a corporation of Ohio

Application May 5, 1934, Serial No. 724,196

3 Claims. (Cl. 91—68.3)

My invention relates to double-walled vacuum containers of glass, and its object is to provide a container of that type in which the silvered walls of the vacuum space have a clear strip like a window for observing the contents of the container. This window is produced by inserting a suitable member into the vacuum space and holding it in firm contact with opposite portions of the walls while these are being treated with a silvering solution. When the silvering operation is finished, the glass areas covered by the inserted member remain unsilvered and transparent to serve as a sight opening.

In practice I have obtained satisfactory results by means of a flexible rubber tube, which is easily inserted into the vacuum space of the container through the usual evacuating tubulation. The inserted tube is then inflated and thereby forced into firm contact with opposite areas of the walls, and these areas are not reached by the silvering solution, but remain clear glass. The tube is thereupon deflated and withdrawn.

The novel features and practical advantages of my invention will be understood from a description of the accompanying drawing, in which

Fig. 1 is a vertical section of a double-walled glass container with a rubber tube inserted into the vacuum space prior to the silvering operation;

Fig. 2 is a front view of Fig. 1, showing the vertical window formed in the container by use of the rubber tube;

Fig. 3 shows a modification in which the inserted tube is looped at its inner end to cover a circular area which shall remain unsilvered; and

Fig. 4 shows a double-walled container having a sight opening formed by the looped tube of Fig. 3.

In all the views there is a double-walled cylindrical container of glass, comprising an outer wall 10 and an inner wall 12 integrally united and separated by a space 13, which in the finished jar is evacuated to provide heat-insulation for the contents. The inside wall surface of the vacuum space 13 is silvered to improve the heat-insulating properties of the container, and this silvering is usually done by pouring a silvering solution through the open tubulation 14, and agitating the jar or bottle until a coating of silver is precipitated uniformly on the walls of the vacuum space. The excess solution is then poured off, the silvered chamber is rinsed with clear water, and finally the container is put

through the usual baking and exhausting operations.

In some instances it has been found necessary to observe the contents of the silvered container from the outside, and to make that possible I form a window or sight opening lengthwise of the container by blocking off opposing portions of the vacuum walls during the silvering operation. One way of doing this is shown in Fig. 1, where a straight soft rubber tube 15 is inserted through the tubulation 14, and is then inflated to force it into firm contact with the walls of the vacuum space 13. The inflated tube may be tied with a piece of string 16 at its outer end or held closed in any other practical way. The silvering solution is then poured into space 13 through tubulation 14 or through another hole in the outer wall 10. The container is then rolled or otherwise agitated to bring the solution into contact with the entire wall surface of the vacuum space 13, except where the inflated tube 15 covers the glass. When the silvering operation is finished and the deflated tube withdrawn, there is left an unsilvered transparent strip 17 through which the contents 18 of the jar may be observed.

In Fig. 3, the inserted rubber tube 15 is doubled and is tied at 19 (an elastic band will do) to form a loop 20, which covers a circular area on each wall of the vacuum space. Consequently, when the looped tube 15 is withdrawn after the silvering operation (the tube being deflated for that purpose), the window 21 formed in the silvered walls has a disk-shaped enlargement 22 at the top. Manifestly, other forms of window may be produced by varying the shape of the inserted member to block off such portions of the glass as may be required in any particular case.

I want it understood that my invention is not limited to the details set forth, for changes and modifications may be made within the scope of the appended claims. Throughout the description and claims I use the term "vacuum space" to designate the space between the two walls of the nested glass cylinders, irrespective of whether a vacuum is actually drawn therein or not. In some double-walled bottles and jars this space is sealed off at atmospheric pressure, or it may be filled with carbon dioxide gas or other medium having heat-insulating properties. All such double-walled containers have a "vacuum space" within the broad meaning of the term as used in the claims. Further, when I speak of the "silvered" walls of the vacuum space, I do not necessarily mean a coating of silver, but I include

any silver-like or mirror-like coating, such as, for example, nickel, magnesium, copper, and so forth.

I claim as my invention:

- 5 1. In the manufacture of double-walled vacuum containers, the method of forming an unsilvered window in the silvered inner walls of the vacuum space, which method comprises inserting a member into said space and maintaining it in firm contact with opposing portions of said walls along a sufficiently wide area substantially lengthwise of the container, and treating said inner walls with a silvering solution while said member is held in place, whereby the opposing wall surfaces covered by said member remain unsilvered and transparent to serve as a window or sight opening, the inserted member being then withdrawn.
- 10 15 2. In the manufacture of double-walled vacuum containers, the method of forming an unsilvered window in the silvered inner walls of the vacuum space, which method comprises inserting an expansible elastic member into said space and forcing it into firm contact with opposing portions of said walls along a sufficiently wide area sub-

stantially lengthwise of the container, and treating said inner walls with a silvering solution while the expanded member remains in contact with said walls, whereby the opposing wall surfaces covered by said member remain unsilvered and transparent to serve as a window or sight opening, the inserted member being then withdrawn.

5 10 15 20 3. In the manufacture of double-walled vacuum containers, the method of forming an unsilvered window in the silvered inner walls of the vacuum space, which method comprises inserting an inflatable rubber tube into said space, inflating the inserted tube to force it into firm contact with opposing portions of said walls along a sufficiently wide area substantially lengthwise of the container, and treating said inner walls with a silvering solution while the inflated tube remains in position, whereby the opposing wall surfaces covered by the inflated tube remain unsilvered and transparent to serve as a window or sight opening, the inserted tube being then deflated and withdrawn.

ARTHUR H. PAYSON.
